(57) **CLAIM**

We claim the ornamental design for a liquid disinfectant dispenser, as shown and described.

DESCRIPTION

FIG. 1 is a perspective view of the liquid disinfectant dispenser of the present invention within the environment of an exemplary bottle shown in broken lines and forming no part of the claimed design;

FIG. 2 is a top plan view thereof;

FIG. 3 is a bottom plan view thereof;

FIG. 4 is a left-side elevational view thereof;

FIG. 5 is a front elevational view thereof;

FIG. 6 is a back elevational view thereof; and,

FIG. 7 is a right-side elevational view thereof.
